(57) **CLAIM**

The ornamental design for a camera friction arm as shown and described.

DESCRIPTION

FIG. 1 is a rear perspective view of a camera friction arm showing our new design;

FIG. 2 is a front perspective view thereof;

FIG. 3 is a left view thereof;

FIG. 4 is a right view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines illustrates portions of the camera friction arm that form no part of the claimed design.

1 Claim, 8 Drawing Sheets
